UNITED STATES PATENT OFFICE.

FRED UTTLEY, OF ELMHURST, NEW YORK.

LOOM-CARD-PEGGING MACHINE.

Application filed March 22, 1922. Serial No. 545,704.

To all whom it may concern:

Be it known that I, FRED UTTLEY, a citizen of the United States, residing at Elmhurst, in the county of Queens and State of New York, have invented a certain new and useful Loom-Card-Pegging Machine, of which the following is a specification.

This invention is a machine for pegging loom cards and more particularly a machine for accomplishing this purpose in an expeditious and accurate manner.

It is well understood by those skilled in the art to which the present invention pertains that the pegging of the loom cards must be changed to effect changes in design and for any particular design a particular set up or arrangement of the pegs on the card must be provided. The cards usually employed are of wood and are provided longitudinally with two rows of openings or holes into which the pegs may be screwed, the particular holes into which the pegs are screwed serving to control the design desired when such a card is subsequently used in the loom. The pegs used are of metal and are provided intermediate their ends with a shoulder or flange. That portion of the peg between the flange and one end of the peg is generally threaded with, for example, a four to one thread while the opposite side of the flange is polygonal to receive a wrench by means of which the pegs may be screwed into the holes of the card. The wrench exclusively employed at the present time is a socket wrench provided at one end with a handle adapted to be held in the palm of the operator's hand and manually manipulated to screw the pegs into the holes of the card individually. That is to say, under the present practice, the workman picks up one peg at a time, introduces it into the end of the wrench and thereupon screws the peg into position on the card. This practice is tedious, requires considerable time and also necessitates the employment of skilled workmen of long experience to accurately position the pins or pegs on the cards in the manual manner described.

With the foregoing considerations in mind the object of the present invention is to provide a machine which will, in effect, automatically mount the pegs on the cards, and which may so operate as to simultaneously mount a large number of these pegs on a card at one operation.

While the present invention may partake of different practical forms it may, to advantage, embody means for holding a loom card in position to receive the pegs adapted to be associated therewith, means for selectively feeding a plurality of pegs into position to be applied, and means for simultaneously forcing a plurality of such pegs into predetermined, proper positions on the cards. By the employment of the present invention the pegs may be applied to a card with ease, accuracy and dispatch, thereby minimizing on time consumption and eliminating errors which frequently occur under the manual operation hereinbefore referred to.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a plan view of a machine embodying the present invention, shown partly in section in the interest of clearness.

Figure 2 is a vertical section on the line 2—2 of Figure 1.

Figure 3 is a horizontal section on the line 3—3 of Figure 2.

Figure 4 is a fragmentary perspective view showing in detail the operation of mechanism for feeding the pegs to be applied to the cards.

Figure 5 is a section corresponding to the sectioned part of Figure 1 but showing the parts shifted into different positions.

Figure 6 is a fragmentary section illustrating the operation of certain peg feeding means shown in Figure 2, and

Figure 7 is a fragmentary perspective view of one end of a conventional form of loom card.

In the accompanying drawings I have illustrated the machine in a more or less diagrammatic way in order that the operations thereof may be clearly understood. In this showing 1 designates any suitable support such, for example, as a bench or table top. On this support 1 is fixed a frame 2. In the upper portion of the frame a carrier roll or conveyor 3 is mounted for

rotation on its axis and preferably has bearings within the bearing blocks 4 and 5 which are secured against rotation but are slidably mounted in a direction longitudinally of the roll 3 in supporting blocks 6 and 7. As clearly shown in Figures 1 and 5, the bearings 4 and 5 are adapted to slide in the blocks 6 and 7 in angular relation to the axis of the roll and this angle is preferably 45 degrees so that the axis of the roll will be shifted in a radial direction the same distance as the roll is shifted longitudinally. The purpose of this shifting will be hereinafter more fully described 10 and such shifting may be accomplished in any suitable way, but for purposes of illustration I have shown one of the bearings 4 as provided with a projection having therein slots 8, with which slots a bifurcated 15 lever is adapted to engage and through the action of this lever, operated in any suitable way, the roll may be shifted longitudinally and, simultaneously, radially.

The roll, which constitutes the carrier for 20 the cards to which the pegs are to be applied, is provided in its outer circumference, with depressions or recesses in the form of pockets 9 so shaped as to form a seat for, and receive therein, a plurality of loom cards, a 25 portion of one of which is shown in Figure 7. The pockets 9 are preferably spaced equidistant about the circumference of the roll as shown in Figure 2 and each pocket is shaped so that one card is adapted to fit 30 into each pocket. In practice, the cards may be linked or chained together in the manner in which they are used on the loom and thereafter fed into the pockets in succession as the carrier roll 3 is revolved, or they may 35 be positioned in the pockets in any suitable way and maintained therein in any desirable manner.

The carrier roll 3 serves, in the machine of this invention, as a support for the cards 40 to be operated upon and its function is to hold the cards in succession in a position to receive the pegs which are applied thereto in an automatic manner as hereinbefore more fully described. In order, however, 45 that the roll 3 may be held against rotation while the pegs are being applied to any particular card one of the shafts or spindles which support said roll has preferably fixed thereto some means of accomplishing this 50 end. A very simple construction for accomplishing this result is shown in Figure 2 wherein a collar 11, having the same number of flat sides as there are pockets in a roll, is fixed on one of the spindles of said roll 55 and a spring 12 bears against this collar in such manner as to preclude inadvertent rotation of the roll and to hold it steady while the pegs are being applied.

The pegs are applied by means of a plurality of plungers or wrenches 13. In a con-

ventional card there are two rows of peg holes 10^a and 10^b of twenty-five holes each (see Figure 7) and the holes of these rows are staggered. For operating upon a card of this character, I preferably employ 70 twenty-five plungers or wrenches 13 positioned at successive distances apart equal to the distance between centers of the holes in either row. These plungers are mounted for vertical reciprocation in the transverse parts 14 of the frame and in such relation to the carrier roll 3 that when the carrier roll is at rest, all the plungers will be coaxial with one row of holes 10^a of the superimposed card 10' supported on the carrier roll 3 in 75 a position to be operated upon, as shown in Figure 2. All of the plungers 13 are the same length and their lower ends are adapted to rest at all times upon an operating bar 15 which extends transversely of the machine and underlies the lower ends of the plungers. The operating bar is mounted for vertical movement and is adapted to be so moved by means of one or more cams 16 80 fixed on a rock shaft 17 which is journaled in the ends of the frame 2. An operating handle 18 is also secured to the rock shaft 17 and by manipulating this operating handle 18 the cams 16 may be shifted for the purpose of causing the raising or lowering of the operating bar 15 to the end that the plungers 13 may be moved toward and retracted from the card 10'.

Each plunger is provided in its upper end with a socket 13^a adapted to receive the shank of a peg. When the handle 18 is operated to elevate the plungers, said plungers will be forced upwardly with the result that any pegs carried by said plungers will be forced into the aligned apertures 10^a of the superimposed card. It will be noted from Figure 2 that the lower end of each plunger is rounded and, in practice, the plungers themselves are mounted for rotation within the frame parts 14 so that said plungers may freely rotate while forcing the pegs into the holes of the card. After the pegs have been forced into position the handle 18 is raised, thereby permitting the plungers 13 to be retracted by gravity, leaving the pegs in position. The weight of the handle 18 may, if desired, be counterbalanced in any suitable way as by a spring 18^a.

In the manner described, the handle 18 110 may be operated for applying a plurality of pegs simultaneously to the holes 10^a of the card. It will be apparent, moreover, that if the carrier roll 3 is shifted longitudinally in its 45 degree angular bearings the card 10' 115 will be bodily shifted to a position wherein the apertures or holes 10^b in the card will go into alignment with the respective plungers. In this way the pegs may be applied first to the holes 10^a and the carrier roll 3 then 120 shifted, whereupon the pegs may be intro- 125 duced into the holes 10^b.

duced into the holes 10^b. By this construction, I am able to peg fifty holes through the use of twenty-five wrenches.

It will be apparent from what has been said that when the plungers are elevated all of them which carry pegs will simultaneously force the pegs in position. Accordingly, the positioning of the pegs in the various holes of the card may readily be controlled by selective feeding of the pegs to only such plungers as it is desired to have effect a pegging operation and, in accordance with this invention, I have devised novel and efficient means for selectively feeding such pegs to the plungers. While this means may vary without departing from the broad scope of the present invention, I have shown in the drawings an efficient method of producing this result.

Thus, in Figure 1, I have shown a hopper 19 mounted on the fixed support 1 forwardly of the frame 2. This hopper is adapted to contain a supply of pegs and, from the hopper, a plurality of tracks lead to the respective plungers. Each track embodies two parallel strips 20 forming between them a guide channel 21 which leads from the hopper to the socket 13^a of the corresponding plunger. The tracks, as shown in Figure 2, are inclined so that such pegs as mount the tracks will gravitate in the direction of the plungers.

The tracks 20 project well into the hopper 19 as shown in Figure 2 and a portion 22 of the bottom of the hopper is made movable and is guided for vertical movement. The portion 22 is surmounted by a plurality of upwardly projecting parallel teeth or webs 23 which impart to the movable portion 22 the shape of a comb, the teeth of which are adapted to extend upwardly between adjacent tracks 20 and the upper edges of which teeth are beveled in lateral directions and slope rearwardly, as clearly shown in Figures 2 and 4. One end of the comb member 22 is secured by means of a pivoted link 24 to the handle 18 while the other end is similarly secured by the link 24^a to an arm 25 which is secured to the rock shaft 17. Accordingly, the movement of the handle 18 will impart vertical movement to the comb member 22 with the result that the comb member will be raised or lowered from the dotted line position of Figure 4 to the full line position of Figure 4 and vice versa. When the comb member is raised it will elevate such of the pegs as have fallen between the tracks 20 and cause them to be tumbled laterally so that when the comb is depressed certain of these pegs will be left in a position to slide down the inclined tracks. In practice, the screw end of the peg is shorter and lighter than the other end thereof so that the pegs will automatically fall screw end up and will

in this position successively slide down the inclined tracks. I have found in practice that the mechanism described will position the pegs on the tracks with unusual efficiency since the movable bottom portion 22 effects efficient agitation and manipulation of the pegs to automatically position them on the tracks in the manner specified. The entire bottom of the hopper may be made movable, if desired, but I preferably make only a portion of the bottom movable and incline the remaining portion of the bottom as shown at 22^a. The pegs deposited on the tracks 20 in the manner described gravitate along these tracks in such manner as to be delivered from the lower end thereof in positions to fall into the sockets 13^a of the associated plungers. It is essential, however, that the movement of these pegs be regulated so as to control the feed of pegs to only those plungers which it is desired to have function at any particular operation of the machine. While this end may be accomplished in different ways I preferably associate with the lower end of each track a pair of cooperating feed fingers 26 and 27, a portion of each finger being in the form of a rack adapted to mesh with an intermediate idler gear 28. The normal position of the parts is as shown in Figure 6 in full lines, wherein the finger 26 is elevated and the finger 27 is depressed. It will be noted from Figure 6 that the finger 26 is at this time holding the pegs in restraint. If the finger 27 is now elevated, the idler gear will cause a simultaneous depression of the finger 26 so that the finger 26 will be withdrawn from in front of the first peg *x* while the finger 27 will be projected upwardly between the first peg *x* and the second peg *x'*, after the manner shown in Figure 2, with the result that the first peg *x* will be released by the withdrawal of the finger 26 while the finger 27 simultaneously restrains the second peg *x'*. Moreover, as the finger 27 approaches the upper end of its travel it is freed from contact with the finger 26 and immediately engages a stop in the form of an adjustable set screw 27^a. As a result of such engagement, the finger 27 is forced quickly forward onto the top of finger 26 as shown in Figure 2. Through this forward action the first peg *x* will be quickly impelled forward and into a position wherein it will fall into the socket 13^a.

While the feed fingers 26 and 27 may be operated in different ways, I have found it highly efficient to control them from finger keys. Thus, I associate with each finger 27 a lever 29 pivoted at 30 and provided at its forward end with a finger key 31. If the finger key 31 is pressed down the feed finger 27 will be obviously elevated and the finger 26 simultaneously depressed so

as to feed one peg *x*. There are feed fingers 26 and 27 associated with each track and each pair of cooperating feed fingers are controlled by a finger key. All of these finger keys may be grouped after the manner shown in Figure 1 and may bear suitable identifying numbers, letters or symbols.

It will appear from the foregoing description, that the pegs to be fed to the respective plungers may be controlled through the manipulation of predetermined finger keys 31. That is to say, the finger keys 31 provide means for selectively controlling the feed of pegs to the plungers so that certain plungers may be included while others are excluded. Thus, in order to obtain the desired pegging for any particular set up it is only necessary for the operator to operate the proper keys in order to provide the appropriate wrenches with pegs, whereupon the handle 18 may be forced down to simultaneously apply all of said pegs to the card. It will be noted that after the operation of each key the feed finger 27 associated therewith is left in elevated position. However, when the handle 18 is forced down and the operating bar 15 elevated, it will engage all of the fingers 26 which have been depressed and so return all of these depressed fingers into their normal elevated positions, simultaneously depressing the raised fingers 27 and leaving the machine in position to be operated for a new set-up.

An important feature of the present invention resides in the fact that by introducing the pegs mechanically and accomplishing this result in such manner as to introduce a plurality of pegs at each operation, the pegging of a card is accomplished much more rapidly than it could possibly be done manually. Moreover, the positioning of the pegs is absolutely reliable and accurate so that greater speed of operation is not only secured but absolute accuracy. Furthermore, the cards to be operated upon are firmly held in position while the pegs are applied thereto, thereby greatly facilitating the work.

The invention is capable of certain other modifications, as by the substitution of equivalents, without departing from the invention. So far as I am aware, the present invention is the first for mechanically pegging loom cards. It is not possible to show all of the various modifications of which the machine is capable and, accordingly, this invention is to be understood as broadly novel as is commensurate with the appended claims.

Having thus fully described the invention, what I claim as new and desire to secure by Letters Patent is:

1. A loom card pegging machine embodying means for holding the loom card in po-

sition to receive a plurality of pegs, means for simultaneously applying a plurality of pegs to the card, and means for selectively feeding variable numbers of pegs in variable arrangements to the peg applying means. 70

2. A loom card pegging machine embodying means for supporting a loom card in position to be operated upon, means for simultaneously pressing a plurality of pegs into the card, and means for selectively feeding pegs in different numbers and combinations to the pressing means. 75

3. A loom card pegging machine embodying means for supporting a loom card in position to be operated upon, a plurality of movable members, each of which is adapted to apply one peg, means for selectively feeding pegs to certain of such members to the exclusion of the others, and means for simultaneously forcing a plurality of such members in the direction of the card to simultaneously apply a plurality of pegs to the card. 80 85

4. A loom card pegging machine embodying means for holding the loom card in position to be operated upon, means for selectively positioning a plurality of pegs in position to be applied to the card, and means for simultaneously applying to the card a plurality of pegs so positioned. 90 95

5. A loom card pegging machine embodying means for supporting a card in position to be operated upon, finger key operated means for selectively positioning a plurality of pegs in positions to be applied to the card, and means for simultaneously applying a plurality of such pegs to the card. 100

6. A loom card pegging machine embodying means for supporting a loom card in position to be operated upon, a plurality of plungers positioned coaxially with holes in the card and provided with sockets adapted to receive pegs, means for positioning pegs in the sockets of said plungers, and means for forcing the plungers in the direction of the card to effect the introduction of such pegs into the holes of the card. 105 110

7. A loom card pegging machine embodying means for supporting a card in position to be operated upon, a plurality of plungers positioned coaxially with holes in the card and provided with sockets adapted to receive pegs, means for selectively feeding pegs into the sockets of predetermined plungers, and means for simultaneously forcing the plungers in the direction of the card to apply such pegs to the card. 115 120

8. A loom card pegging machine embodying means for supporting a card in position to be operated upon, means for selectively feeding pegs one at a time into alinement with certain predetermined holes in the card into which said pegs are to be subsequently introduced to the exclusion of the other holes therein, and means for there- 125 130

after forcing a plurality of the pegs thus fed simultaneously into the holes of the card.

9. A loom card pegging machine embodying means for holding the card in position to be operated upon, a plurality of peg holding members, a hopper, means for guiding pegs from the hopper to the respective peg holders, means for selectively controlling the feeding of pegs from the guide means to the peg holders, and means for operating a plurality of peg holders to simultaneously force a plurality of pegs into the cards.

10. A loom card pegging machine embodying means for holding a card in position to be operated upon, means for simultaneously pressing a plurality of pegs into one series of holes in the card, means for thereafter shifting the card to bring another series of holes into positions to receive pegs, means for thereupon simultaneously pressing a further series of pegs into the card.

11. A loom card pegging machine embodying means for supporting a loom card in position to be operated upon, means for bringing a plurality of pegs into position to be simultaneously introduced into certain holes in the card, means for simultaneously forcing such pegs into said holes, and means for shifting the card so that additional pegs may be placed in the other holes of the card.

12. A loom card pegging machine embodying means for supporting a loom card in a position to be operated upon, a plurality of plungers each of which is mounted for reciprocation co-axially of one of the holes in the card, means for delivering pegs into proximity with a socket in each of the plungers, means for selectively feeding pegs into the sockets of the plungers, and means for simultaneously reciprocating a plurality of the plungers for the purpose of simultaneously forcing the pegs supported thereby into the holes in the card.

13. A loom card pegging machine embodying means for holding a loom card in position to be operated upon, a plunger provided with a socket and adapted to be longitudinally reciprocated co-axially of one of the holes in the card, a track for feeding pegs into proximity with the socket of the plunger, a plurality of feed fingers adapted to be simultaneously operated for the purpose of feeding the pegs one at a time into the socket of the plunger, and means for thereupon reciprocating the plunger to force the peg thus fed into the aligned hole of the card.

14. A loom card pegging machine embodying means for holding a loom card in position to be operated upon, a movable member adapted to support a peg in posi-

tion to be applied to the card, and means for operating said member to apply the peg to the card, in combination with a hopper provided with a movable bottom adapted to be operated simultaneously with the movable member for the purpose of agitating pegs contained in the hopper, tracks adapted to receive the pegs thus agitated and to convey said pegs into proximity with the movable member, and means for feeding the pegs one at a time to the movable member.

15. A loom card pegging machine embodying means for holding a loom card card in position to be operated upon, a plurality of plungers, each of which is provided with a socket adapted to receive a peg, means for operating a plurality of the plungers to simultaneously apply a plurality of pegs to the card, in combination with a hopper, a track leading from the hopper to each plunger, a movable bottom member in the hopper provided with upstanding comb-like projections extending between the several tracks and adapted to be vertically reciprocated between said tracks to agitate the pegs in the hopper and cause them to be delivered onto the tracks which are inclined to permit the pegs to gravitate in the direction of the plungers, feed fingers for delivering pegs one at a time to the plungers, and means for selectively operating said feed fingers to control the delivery of pegs to predetermined plungers.

16. A loom card pegging machine embodying means for simultaneously applying a plurality of pegs to a card, in combination with means for delivering the pegs into positions to be applied, embodying a hopper adopted to contain pegs, a plurality of inclined tracks leading from the interior of the hopper to substantially the point of application, a movable bottom in the hopper, which bottom is provided with upstanding webs projecting between the several tracks, and the upper edges of which webs are inclined in a direction opposite to the inclination of the tracks, and means for vertically reciprocating the movable bottom for the purpose of agitating the pegs and causing them to be tumbled onto the tracks.

17. A loom card pegging machine embodying a plurality of movable members each of which is adapted to support a peg, means for selectively delivering pegs to certain of said movable members to the exclusion of the others, and unitary means for simultaneously operating the members to simultaneously apply all of said pegs, thus delivered, to a loom card.

In testimony whereof I have signed the foregoing specification.

FRED UTTLEY.
